UNITED STATES PATENT OFFICE

2,404,265

NOISE-MAKING AIRPLANE TOY

Harry Zimmerman, New York, N. Y.

Application December 2, 1944, Serial No. 566,299

2 Claims. (Cl. 46—52)

1

My invention relates to toys which produce a noise when whirled through the air.

Objects of my invention are to provide a toy with a movable part which is operated by the relative air current when the toy is whirled, to attach such a part rotatably to a whirly body, to operate a drum or a similar noise making instrument by such a part, and to produce a crackling or rattling noise by a whirling toy.

Other objects are to whirl a toy of this kind by a string or similar flexible means, to affix a string or any other holding element about over the center of gravity of the toy, to provide the toy with a reverberating or loud sounding element, to provide the toy with an element adapted to strike this reverberating element or to cause the same to reverberate, to make this striking element resilient, to bring the same periodically into a tensed position, to release the striking element periodically from this position, and to obtain loud sounds by strokes of an element released from a tensed condition.

Further objects are to provide a toy of this kind with a shape simulating an airship or airplane, to provide means directing the toy into a definite direction when the toy is whirled, to provide the toy with wings and with tail rudders, to provide the toy with a rotary propeller, to provide the toy with a noise making device simulating the noise of an engine or of a machine gun, and to operate this device by a propeller driven by air current.

Still other objects are to obtain these results with simple, inexpensive and efficient means, and in a manner capturing the fancy of a child.

Still further objects and advantages will appear from the following description of an exemplifying embodiment of the invention, from the appended claims and from the accompanying drawing in which:

Fig. 1 shows a side elevation of an illustrative embodiment.

Fig. 2 shows an elevation of the same embodiment seen from the upper side in Fig. 1, a part of a wing being broken off for the sake of better representation of certain parts positioned below this wing.

Referring to the drawing, numeral 1 indicates a body which may be made of a flat sheet of any suitable material, for example of cardboard, and which is preferably cut according to the outlines of an airplane, the left, front part of the body 1 simulating the engine casing and cockpit, and the right rear end of the body simulating a vertical rudder. A plate 2 simulating the wings of the

2

airplane may be connected to the body 1, for example by passing the plate 2 through a slot provided in the body 1. A plate 3 simulating horizontal rudders may be connected to the rear part of the body 1 in a similar manner.

A shaft 4 is rotatably carried by a bearing 5 affixed to the body 1. The shaft 4 has a laterally extending part or crank 6. An opening 7 cut out in the body 1 permits the crank 6 to rotate together with the shaft 4. A second bearing 8 may be provided at the other side of the opening 7. The bearings 5 and 8 may be constructed in any suitable manner. For example, they may be formed by cylindrically bent parts of a thin metal plate 9 affixed to the body 1 in any suitable manner, for example by rivets 10.

A propeller 11 is concentrically affixed to the shaft 4, for example by soldering the propeller to an angularly bent end 12 of the shaft. The propeller 11 may be made of metal or any other suitable material. For example, the propeller may be cut out of a sheet of metal and may be bent at the two ends in opposite directions whereby the air current hitting the propeller in the direction of the shaft 4 will turn the propeller and the shaft.

A reverberating plate 13 which may be the upper plate of a drum 14 is affixed to the body 1. The plate 13 or the entire drum 14 may be made of any suitable material, for example of cardboard, and the drum may have a longitudinal slot for the passage of the plate 9.

A resilient arm 15 has one end affixed to the body 1, for example, by a rivet 16. The other end of the arm 15 is positioned over the plate 13, has a part 17 bent down into contact or almost into contact with the plate 13, and has a part 18 positioned in the path of the crank 6. The arm 15 may be a narrow strip of thin sheet metal which is so twisted that the affixed end is parallel to the body 1 and that the remaining parts of the arm are parallel to the plate 13. The arm 15 may pass through an opening provided in a ledge 19 which may be formed by an integral part of the plate 9 bent at a right angle relative to the body 1.

A string 20 of which only a short part is shown is affixed to the body 1, preferably at a point positioned about vertically over the center of gravity 50 of the body. The string may be affixed in any suitable manner. For example, the affixed end of the string may form a loop passing through a hole provided in the body 1.

The described toy operates as follows:

A hand of the playing person holds the string

20. When the toy is suspended in this way idly, it represents a horizontally flying airplane and may swing like a pendulum. The elongations of the swinging body may be increased by suitable movements of the hand. By sufficient suitable movement of the hand, the toy is whirled in a circular way in a plane that may be vertical, horizontal or obliquely tilted as desired.

As soon as the whirling or swinging movement has sufficient speed, the air resistance or the relative air current causes the propeller to rotate whereby the crank 6 rotates and, at each turn, hits the part 18 of the arm 15. Preferably and as shown in the drawing, the turning direction of the propeller 11 is so chosen that the crank hits the part 18 from the lower side or from the side where the drum 14 is positioned.

The sizes and positions of the surfaces of the toy, particularly of the wings 2 and the rudders 3, and the distribution of weight are so chosen that the air resistance directs the body 1 into a position where the propeller leads and the tail follows or where the air current hits the propeller in axial direction.

The crank 6, having hit the part 18, lifts the arm 15 somewhat and, then, rotating further around the axis of the shaft 4, toward the position shown in the drawing, moves to the side, thereby releasing the part 18. Upon this release, the arm 15 which, by the lifting movement, has acquired a tensed condition swings resiliently back and strikes the plate 13 of the drum 14 with considerable force whereby a loud noise or sound is produced. This stroke is repeated at each turn of the propeller 11 or the crank shaft 4 and gives an impression surprisingly resembling the noise produced by an airplane engine or by a machine gun.

I desire it understood that my invention is not confined to the particular embodiment shown and described, the same being merely illustrative, and that the invention may be carried out in other ways without departing from the spirit of the invention as it is obvious that the particular embodiment shown and described is only one of the many that may be employed to attain the objects of my invention.

Having described the nature of my invention and how it operates, what I claim and desire to secure by Letters Patent is:

1. A toy comprising a body of sheet material having an outline simulating that of the fuselage of an airplane, the body having an opening in its forward portion, a plate of sheet metal mounted against a side face of said body under the opening and having upstanding arms extending along front and rear ends of the opening and provided with bearings, a drum carried by said plate and projecting therefrom laterally of the body, a flange projecting laterally from the rear end of said plate along the rear arm thereof, a strip extending longitudinally of said body and through an opening in said flange and having its rear end secured to the body and its forward portion free and bent to form a depending portion disposed over the drum, a shaft rotatably mounted through said bearings and extending along a side of the body with its front end projecting from the body and carrying a propeller, and a portion of the shaft opposite the opening in the body being bent to form an arm moving through the opening in the body as the shaft rotates and intermittently engaging under the front end of said strip to vibrate the strip vertically and cause its depending portion to have noise-producing contact with the drum.

2. A toy comprising a body simulating the fuselage of an airplane and formed with an opening, bearings at front and rear ends of said opening, a drum projecting laterally from said body along the lower portion of the opening, a resilient strip extending longitudinally of the body at a side thereof and secured at its rear end and having its forward portion opposite the opening provided with a depending striker located over the drum, a shaft extending longitudinally of the body and rotatably mounted through said bearings and having its forward end projecting from the body, said shaft having a radially extending arm moving through the opening during rotation of the shaft and intermittently striking the front end portion of said strip to vibrate the strip and cause its striker to have beating contact with the drum, and a propeller carried by the front end of said shaft.

HARRY ZIMMERMAN.
